UNITED STATES PATENT OFFICE.

WILLIAM J. KENNY, OF CICERO, ILLINOIS, ASSIGNOR TO AMERICAN CAN COMPANY, OF NEW YORK, N. Y., A CORPORATION OF NEW JERSEY.

METHOD OF ATTACHING BAILS TO CONTAINER BODIES.

1,403,169.

Specification of Letters Patent. Patented Jan. 10, 1922.

Original application filed August 18, 1917, Serial No. 187,009. Divided and this application filed December 22, 1919. Serial No. 346,717.

To all whom it may concern:

Be it known that I, WILLIAM J. KENNY, a citizen of the United States, residing in Cicero, in the county of Cook and State of Illinois, have invented a new and useful Improvement in Methods of Attaching Bails to Container Bodies, of which the following is a specification.

This invention relates in general to the assembling of bails on container bodies and has more particular reference to the assembling of bails of the character described in the co-pending application of James H. Doyle and myself, filed August 18, 1917, Serial No. 186,873. This application is a division of my pending application filed August 18, 1917, Serial No. 187,009.

The invention has for its principal object the provision of a simple process of attaching bails of the character described in said Doyle and Kenny application mentioned, to the container body.

A further object of the invention is the provision of a process which will permit the assembling of such bails without requiring complicated or expensive mechanism or the attention of skilled mechanics.

Other objects and advantages of the invention will be apparent as it is better understood from the following description when considered in connection with the accompanying drawing illustrating a preferred form of apparatus.

On the drawing,

Figure 1 is an elevation, partly broken away, of a container having bail ears, partly in section, and united therewith a bail;

Fig. 2 is a perspective view of one of said bail ears and a portion of the bail inserted in said ear but not yet bent or twisted to locked position.

Fig. 3 is an end elevation shown partly in section of a machine adapted to complete the assembling;

Fig. 4 is a section taken transversely of the machine;

Fig. 5 is an enlarged detail view of the device for clamping the bail in the final assembling operation;

Fig. 6 is a section taken substantially on the line 6-6 of Fig. 3; and

Fig. 7 is a similar section showing the parts after the operation is complete.

The bail 11' adapted to be assembled by

the particular machine used to illustrate 55 the present invention, is shown in Fig. 1 from which it will be noted that the two ends 11 are adapted to extend at right angles to the plane of the bail when in attached relation. Just outwardly of the ends 11 are 60 provided two rectangular loops 12 which are disposed in the plane of the bail, the lower part 13 of the wire of each loop extending through the opening 14 in the bail ear 15. The bail thus constructed is assembled in 65 the following manner:

One loop 12 is, in the construction of the bail before attachment, disposed at right angles to its normal position, i. e., at right angles to the plane of the body of the bail 70 and its end 11 is also at right angles to its normal position. The bail is positioned by inserting the end of the bail having the loop in the plane of the body through its bail ear and then turning the bail until the 75 end at the other side can be inserted. The assembling or attachment is completed thereafter by bending the loop at the last mentioned side at right angles to itself to dispose the end 11 completely within the ear 80 and the part 13 of the loop passing through the aperture. The first of these operations can be quickly and easily accomplished by hand and to facilitate the operation of the last or final step I have provided a machine 85 for the bending of the loop as already described.

This machine consists of a holding or clamping block or device 16 together with suitable means for turning it after it has 90 engaged the bail.

On the drawings reference character 17 indicates a main frame of the machine having bearing brackets 18 at its top. Through these bearing brackets a shaft 19 extends 95 and on the end of this shaft the block 16 is secured. This block, in the present instance, is provided with a central channel 21 and is cut away transversely to provide grooved walls 22 in which the bail ear may 100 rest with the loop disposed in the channel as may be observed in viewing Figs. 3 and 5. The side of the block adjacent the container 23 is cut away at 24 to permit the body of the bail to pass from under the influence of the holding device. The bend is effected about the axis of the leg of the bail at the point *a* and it is only necessary that

the holding device clamp the loop when it turns. The side of the holding device away from the container is extended upwardly as indicated at 25 to prevent the bail sliding 5 out of the channel. In this movement the bail is clamped between the outer channel wall, Fig. 6 (which becomes the top channel wall Fig. 7), at *b* and the inner channel wall, (which becomes the bottom wall), at *c*. 10 When the clamping device starts its return movement the assembled bail is released and slides out of the channel over the curved surface 30. The shaft 14 is caused to oscillate by a rack 26 connected to a slide 27 moving in ways 27' and an eccentric rod 28 of an eccentric sleeve 28' on an eccentric 29. The rack 26 meshes with a pinion 31 on the shaft 19 so that reciprocation of the 30 rack 26 produces the desired oscillation of the holding device 16. The bending action 35 may be completely observed from Figs. 6 and 7 which also show the method of insertion of the end of the bail. Viewing Fig. 6 it will be noted that the end 11 extends 40 through the aperture 14 and that after the loop 12 has been bent through an angle of 90° its part 13 extends therethrough.

The method of positioning the bails consists of providing loops at the bail ends, 30 one of said loops being disposed under its lateral position and the other arranged angularly with respect thereto, then inserting the first mentioned loop in its bail ear, inserting the second mentioned loop in its 35 bail ear and bending the latter to the same position as the former to lock the parts together.

It is thought that the invention and many of its attendant advantages will be understood 40 from the foregoing and without further description and it is believed that various changes may be made in the steps of the process selected for the purpose of illustration and of course in the apparatus without departing from the spirit and scope of the invention or sacrificing all of its material advantages, the form hereinbefore described being merely a preferred embodiment thereof.

50 I claim:

1. A method of attaching bails to container bodies, which consists in providing

the bail with loops near its ends, inserting the ends of the bail in the bail ears and completing the assembling by turning a loop 55 angularly with respect to the general plane of the body of the bail.

2. A method of attaching bails, having oppositely extending ends, to container bodies, which consists in providing a loop 60 adjacent one end, inserting the ends in the bail ears and turning the loop and its end angularly with respect to the general plane of the body of the bail to complete the assembling.

3. A method of attaching bails to container bodies, comprising providing loops at the bail ends, one said loop being disposed angularly with respect to its final position and to the plane of the bail, inserting the end 70 beyond said loop in the bail ear and bending the angularly disposed loop to the plane of the bail.

4. A method of attaching bail ends to container bodies which are provided with laterally presented apertures, which consists in forming the end of the bail with a loop 75 arranged in a plane which is at an angle to the general plane of the bail and with an end 11 which is at an angle to the lower 80 part of said loop so as to extend towards the aperture of the body, connecting the other end of the bail with the body in a suitable manner, then inserting the end 11 in the aperture of the body, and then twisting 85 said loop into a position substantially in said general plane of the bail, and causing said end to take a transverse position within the aperture, so that the lower part of the loop becomes the pivotal element of 90 the bail and said end the retaining element.

5. A method of attaching bail ends to container bodies which are provided with laterally presented apertures, which consists in forming the end of the bail with a 95 pivot element which extends in a direction transverse to the plane of the bail and a retaining element which is transverse to said pivot element, then introducing said retaining element into the aperture of the body, 100 and then twisting the bail to cause said retaining element to be transverse within said aperture.

WILLIAM J. KENNY.
